John T. Clark
INVENTOR

UNITED STATES PATENT OFFICE.

JOHN T. CLARK, OF PROVO, UTAH.

NECKTIE-HOLDER.

1,393,262.

Specification of Letters Patent. Patented Oct. 11, 1921.

Application filed November 9, 1920. Serial No. 422,842.

To all whom it may concern:

Be it known that I, JOHN T. CLARK, a citizen of the United States, residing at Provo, in the county of Utah and State of Utah, 5 have invented new and useful Improvements in Necktie-Holders, of which the following is a specification.

My invention consists of an improvement on my former invention of necktie holders 10 patented Oct. 14, 1919, No. 1,318,846, and the objects are to provide a more suitable button engaging loop which can be applied to various kinds and sizes of buttons and which is practically invisible while in use 15 and also to provide a more suitable means of connecting the several parts of the device.

I attain these and other objects by the mechanism illustrated in the accompanying drawing in which Figure 1 is a front elevation of the device with parts connected 20 for use with a low collar. Fig. 2 is a front elevation with parts connected for use with a high collar and showing the position of engagement with the collar button. Fig. 3 25 is a side elevation of the middle loop of the device shown in Fig. 1 and also showing the position of engagement with the collar button. Fig. 4 is a front elevation of the device showing the tie in position for use.

30 In the several figures of the drawing letter A designates a piece of spring wire which is bent at the middle forming a return bed 1 and two short parallel portions of wire 2, 2. Thence the wire turns backward forming 35 two bends 3, 3 best shown in Fig. 3. Thence the wire is given sharp lateral bends forming the lobes 4, 4 and then crosses at the point 5. In the diverging end portions of the wire are formed any desired number of 40 loops 6, 6 and after making broader turns 7, 7 the end portions terminate in small loops 8, 8. The holes 4, 4 are adapted to fit astride the stem 9 of the collar button while the rim 10 of the button fits up into the curves 3, 3 45 as shown in Figs. 2 and 3. The short parallel portions 2, 2 and curve 1 form a handle by which the wire may be set upon the button or detached from it, and also form a brace to hold the tie away from the collar 50 button. The resilient member 11 upon which the tie is supported may preferably consist

of one or more rubber bands and is provided at each end with suitable tips or links or connections 12, 12. These tips may preferably consist of rings fastened to the elastic 55 bands 11. The rings 12, 12 may be set in the loops 8, 8 or in the loops 6, 6 according as the collar is high or low, or may be detached from the wire A entirely without disturbing the setting of the tie on the band 11. 60 A number of these bands 11 with rings at the ends may be provided and ties hung upon them. The ties will then be readily interchangeable upon the wire A.

The broad loops 7 fit between the folds of 65 the collar and present a large surface of contact which prevents injury to the collar.

I claim:

1. A necktie holder comprising a piece of 70 spring wire with a button engaging loop medially therein, said loop consisting of a central return bend adapted to project in front of the collar button, two anterior bends adapted to rest on opposite sides of the upper surface of the rim of the collar button, 75 and two lateral bends adapted to fit astride the stem of the collar button; one or more side loops in each free end of the wire; and an elastic band connecting a pair of said side loops. 80

2. A necktie holder comprising a piece of 85 spring wire having a button engaging loop medially therein, said loop containing oppositely located bends adapted to fit astride the stem of the collar button, and one or more side loops in each free end of the wire, and resilient means connecting a pair of said side loops.

3. A necktie holder comprising a piece of 90 spring wire with a button engaging loop medially therein, said loop consisting of a central return bend adapted to project in front of the collar button, two anterior bends adapted to rest on the opposite sides of the upper surface of the rim of the collar button, 95 and two lateral bends adapted to fit astride the stem of the collar button; one or more side loops in each free end of the wire; and an elastic band provided with links and connecting a pair of said side loops.

JOHN T. CLARK.
